UNITED STATES PATENT OFFICE.

CHARLES MAHÉ DE CHENAL DE LA BOURDONNAIS, OF LOVENTOR MANOR, NEAR
TOTNES, ENGLAND.

DESIGN FOR A TONE ARM FOR A GRAMOPHONE OR SIMILAR ARTICLE.

Application filed December 26, 1924. Serial No. 11,804. Term of patent 14 years.

To all whom it may concern:

Be it known that I, CHARLES MAHÉ DE CHENAL DE LA BOURDONNAIS, PRINCE DE MAHÉ, a subject of the King of Great Britain and Ireland, residing at Loventor Manor, near Totnes, in the county of Devon, England, have invented a new, original, and ornamental Design for Tone Arms for a Gramophone or Similar Article, of which the following is a specification, reference

being had to the accompanying drawings, forming part thereof.

Fig. 1 is a side elevation, and Fig. 2 is a plan view of a tone arm showing my new design.

I claim:

The ornamental design for a tone arm for a gramophone or similar article, as shown.

CHARLES MAHÉ de CHENAL de la
BOURDONNAIS, PRINCE de MAHÉ.
